UNITED STATES PATENT OFFICE.

LUDWIG SPADY, OF PORTLAND, OREGON.

DISAPPEARING IRONING-BOARD ATTACHMENT FOR KITCHEN-TABLES.

1,140,411.

Specification of Letters Patent.

Patented May 25, 1915.

Application filed July 14, 1914. Serial No. 851,003.

To all whom it may concern:

Be it known that I, LUDWIG SPADY, a citizen of the United States, and a resident of the city of Portland, county of Multnomah, 5 State of Oregon, have invented a certain new and useful Improvement in Disappearing Ironing-Board Attachments for Kitchen-Tables, of which the following is a specification.

10 The object of my invention is to provide the ordinary kitchen table with an ironing board supported under the table-top, sliding in and out under the latter, and provided with means for supporting the board in 15 horizontal position from the table when pulled out. In this way the ironing board is never in the way, is protected from dust when not used, and is ready for use as soon as pulled out from the table, without requiring a chair or other support.

20 The details of construction and operation of my invention are hereinafter fully described.

In the accompanying drawings: Figure 1 25 is a side elevation of a table provided with my ironing board attachment, which is shown on the right-hand pulled out and supported in horizontal position, as in practice, by the means with which it is for that 30 purpose provided; Fig. 2 is a longitudinal section of my device approximately taken on line 2—2 of Figs. 3 and 4; Fig. 3 is a bottom view of my device; and Fig. 4 is a section taken on the dotted line 4 of Fig. 3.

35 A represents a table, of ordinary form, comprising legs, *b*, top *c*, side frame members *p*, and end frame members *p'*. Under the top, near the sides, are affixed longitudinal guide-bars *d*, *d'*, slotted at *e*. A transverse carrier *f*, 40 made with laterally projecting portions sliding in the slots, *e*, *e*, of the guide-bars *d*, *d'*, has affixed to it one end of an ironing board *g*. On the under side of the ironing board is affixed, by a hinge *h*, a strut *i*. This strut 45 has a rectangular portion cut out, as at *j* in Fig. 3, and in such cut-out part is pivoted, by means of a pivot *k*, a leg *l*. The leg has a rectangular portion *m*, cut out so as to accommodate the stops, *n*, *n*, affixed to the 50 under side of the ironing board. Compare Figs. 1, 3 and 4. The end of the strut, *i*, has a closing piece, *o*, affixed to it, which closing-piece constitutes the closure for the opening through the side frame member *p'* 55 of the table to the guide-bars *d*, *d'*. The latter are preferably made of two pieces fas-

tened at their ends between the table frame members *p'*, *p'*, as shown in Fig. 3. The opening to the guide element for the sliding board is made just large enough to receive the latter, therefore the carrier *f* acts as a stop preventing the ironing board being entirely drawn out from the table. The closing-piece, *o*, is for convenience made with a hand-hole *q*, as shown in Fig. 3, which also accommodates the nose of the ironing board *g*.

60 The operation of my device is as follows: Seizing the closing piece, *o*, of the strut, *i*, by the hand, the latter is pulled out as far 65 as it can go, the ironing board being meanwhile held by the carrier, *f*, and the latter serving as a stop, as mentioned. The strut is then dropped and the leg, *l*, arranged to support the ironing board in a horizontal 70 position, as illustrated in Fig. 1.

I claim:

1. The combination with a table, of guide elements extending under the table-top, a board slidably supported by such guide elements, a stop preventing the board being entirely withdrawn from the table, a strut hinged to the inner end of the board, a leg pivoted to the strut, a stop on the under side of the board for receiving the top of the 80 leg, and a closing piece affixed on the free end of the strut for closing the opening to said guide elements through the table frame.

2. The combination with a table, of guide elements extending under the table-top, a carrier slidably supported by such guide elements, a board affixed at one end to the carrier, a strut hinged to the inner end of the board, a leg pivoted to the strut, and a closing piece affixed on the free end of the strut 85 for closing the opening to said guide elements through the table frame.

3. The combination with a table, of guide bars arranged under the table top and near the sides, a carrier slidably supported by such guide-bars, the latter comprising each two pieces spaced apart, and the carrier having laterally extending portions sliding 100 in the space between the pieces of the guide bars, a board affixed at one end of the carrier, a strut hinged to the inner end of the board, a leg pivoted to the strut, and a closing piece affixed on the free end of the strut 105 for closing the opening to said guide elements through the table frame.

4. The combination with a table, of guide

bars arranged under the table top and near the sides, a carrier slidably supported by such guide bars, the latter comprising each two pieces spaced apart, and the carrier 5 having laterally extending portions sliding in the space between the pieces of the guide bars, a board affixed at one end to the carrier, a strut hinged to the inner end of the board, the strut having a longitudinal portion cut out, a leg pivoted in such cut-out 10

part of the strut, a stop on the under side of the board for receiving the top of the leg, and a closing piece affixed on the free end of the strut for closing the opening to said guide elements through the table frame. 15

LUDWIG SPADY.
